UNITED STATES PATENT OFFICE.

STEPHEN F. CETTA, OF BROOKLYN, NEW YORK.

BANJO.

1,337,041.

Specification of Letters Patent. Patented Apr. 13, 1920.

Application filed December 8, 1919. Serial No. 343,236.

To all whom it may concern:

Be it known that I, STEPHEN F. CETTA, a citizen of the United States, residing at Brooklyn, in the county of Kings and State of New York, have invented certain new and useful Improvements in Banjos; and I do declare the following to be a full, clear, and exact description of the invention, such as will enable others skilled in the art to which 5 it appertains to make and use the same.

This invention relates to improvements in banjos, and it has more particular reference to an attachment for a banjo which is designed to produce a greater volume and 10 clearer and prolonged tones.

The principal object of the invention is to provide a novel attachment for the above mentioned purpose which is exceedingly simple in construction, the construction being such that it may be readily applied to 20 banjos of ordinary construction and will serve to increase the value and tone qualities.

Other objects and advantages of the invention will become apparent during the course 25 of the following description.

In the accompanying drawings forming a part of this specification and in which like numerals are employed to designate like 30 parts throughout the same,

Figure 1 is a plan view of an attachment constructed in accordance with my invention.

Fig. 2 is a section on the plane of the line 35 2—2 of Fig. 1.

Fig. 3 is a central sectional view of a banjo equipped with my improved attachment.

In the drawings, wherein for the purpose of illustration is shown a preferred embodiment of my invention, the numeral 1 indicates the body or shell of a banjo of ordinary construction. A vibratory head 2 of parchment or other suitable material is stretched across the body and is held in position thereon by means of the metal ring 3. As is well known the head 2 is tightened by means of a plurality of brackets 4 which consist of hooks which engage the ring 3 at one end and have their opposite ends 45 screw threaded and passed through the lugs 5 carried by the body, the ring being drawn down when the nuts 6 are rotated in the proper direction.

My attachment consists of an annular metallic ring 7 which is adapted to be connected in any suitable manner to the upper edge

of the body 1 and a portion of which is designed to bear on the under surface of the head 2 and elevate it at its center to the position shown in Fig. 3. This ring 7 is made 60 of a single piece of metal and is bent between its edges to form a hyperbolic curve, one edge of which forms a vertical flange 8, and the other edge of which is rolled to form a bead 9, upon which the head 2 rests. 65 The portion between the bead 9 and the flange 8 forms a channel, and this portion is provided with a plurality of holes or openings 10, the purpose of which will be hereinafter more specifically described. My attachment may be secured upon the body 1 in any suitable manner, however, I form a notch or groove entirely around the upper edge of the body and seat the flange 8 in this groove, and as the ring 3 bears tightly 70 against the outer surface of the body, it will be seen that the flange 8 will be held tightly between this ring and the body. While I have shown and described the flange 8 as being seated in a groove formed in the 75 body, I desire it to be understood that formation of such a groove is unnecessary, as the flange 8 may also be held in position without this groove, as is obvious.

By means of this attachment, or ring, to 80 a banjo, the tone quality of the instrument will be greatly increased and the volume will likewise be increased, due principally to quicker vibrations of the head caused by raising it above the extreme upper edge of 85 the body of the banjo. The openings 10 also serve to increase the efficiency of the attachment in that they permit the escaping musical vibrations or sounds to pass through them and against the under surface of the portion 90 of the head between the bead 9, and the body 1. Ordinarily this portion is inclined to be somewhat dead, that is, it does not vibrate freely, and by permitting the musical waves to contact with it, it is vibrated slightly, or 95 at least more than it would if the sound waves were not permitted to come into contact with it. With such an attachment, a greater tension upon the head may be had, and the greater the tension of the head the 100 quicker the vibration will be, consequently, the sound waves will be greatly prolonged and more brilliant. My attachment is also designed to prevent, as much as possible, the 105 head from having too much contact in any portion thereof. For this reason I provide a bead 9, which because of its roundness pre-

sents little surface for the head to bear against. It is well known that where the head bears against any parts of the banjo, a bad effect results, that is, the vibratory action of the head is greatly decreased. For this reason it is essential that the surfaces against which the head bears should be decreased as much as possible in order to insure that the head will have free vibration. 10 My attachment is constructed to overcome the above circumstances as much as possible.

I claim:

A banjo comprising a body, an annular metallic ring bent between its edges to form

a hyperbolic curve, one edge thereof forming a vertical flange adapted to rest on the upper edge of the body and the other edge being rolled to form a bead, the portion between the bead and flange forming a channel and being provided with a plurality of 15 spaced openings, a vibratory head stretched across the body and ring, means for retaining the bead in position on the body, and means for tightening the head. 20

In testimony whereof I have hereunto set 25 my hand.

STEPHEN F. CETTA.
